FISH LURE

William Mozuras, Detroit, Mich.

Application March 2, 1949, Serial No. 1,166

Term of patent 14 years

(Cl. D31—4)

To all whom it may concern:

Be it known that I, William Mozuras, a citizen of the United States and a resident of the city of Detroit, county of Wayne, and State of Michigan, have invented a new, original, and ornamental Design for a Fish Lure, of which the following is a specification, reference being had to the accompanying drawings, in which:

Fig. 1 is a perspective view of a fish lure.

Fig. 2 is a top plan view of my fish lure.

Fig. 3 is a side elevation view of the lure showing my new design.

I claim:

The ornamental design for a fish lure, as shown.
WILLIAM MOZURAS.
